(57) CLAIM

The ornamental design for an electrical connector, as shown and described.

DESCRIPTION

FIG. 1 is a front elevational view of an electrical connector showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view showing a front, top and right side thereof;

FIG. 8 is a perspective view showing a rear, bottom and left side thereof;

FIG. 9 is a perspective view showing a front, right side and bottom thereof;

FIG. 10 is a perspective view showing a rear, left side and top thereof; and,

FIG. 11 is a sectional view thereof taken along line 11-11 in FIG. 5.

The broken line showing of the electrical connector is for the purpose of illustrating portions of the article and forms no part of the claimed design.
